La Montana Full Mask w/ Micro-Elite Chamois Mask, [on-line];
[Internet publication date unknown]; [retrieved from the Internet on
Jul. 30, 2018]; URL: <https://www.hotchillys.com/collections/accessories/products/la-montana-full-mask-w-micro-elite-chamois-mask-hc6143>. (2 pgs). (Year: 2018).*

Primary Examiner — Karen S Acker*Assistant Examiner* — Jasmine Mlinarcik(74) *Attorney, Agent, or Firm* — Matthew J. Spark; Stefan
J. Kirchanski; Zuber Lawler & Del Duca LLP(57) **CLAIM**The ornamental design for a face mask with neck warmer, as
shown and described.**DESCRIPTION**FIG. 1 is a perspective view of a face mask with neck
warmer, embodying the invention;

FIG. 2 is a top plan view of the face mask of FIG. 1;

FIG. 3 is a front view of the face mask of FIG. 1;

FIG. 4 is a rear view of the face mask of FIG. 1;

FIG. 5 is a side view of the face mask of FIG. 1; and,

FIG. 6 is another side view of the face mask of FIG. 1.

The broken lines illustrating a figure wearing the face mask
with neck warmer depict environmental subject matter that
forms no part of the claimed design.**1 Claim, 4 Drawing Sheets**---
